UNITED STATES PATENT OFFICE.

WALTER H. WAKEFIELD, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

REED HOLDER.

Application filed February 11, 1924. Serial No. 691,930.

To all whom it may concern:

Be it known that I, WALTER H. WAKEFIELD, a citizen of the United States, residing at Worcester, in the county of Worcester and State of Massachusetts, have invented new and useful Reed Holders, of which the following is a specification.

This invention relates to loom reeds and more particularly to an improved reed holder whereby the reed may be given a plurality of fixed vertical positions with respect to the lay.

In looms as ordinarily constructed the lay is provided with a slot in which is mounted a reed holder so formed as to receive the lower part of the reed and there is also provided a hand rail or reed cap into which the top of the reed extends. As weaving continues it is found that the wires or dents from which the reed is formed develop slight notches at the point where the filling is beaten into the fell of the cloth. In order to avoid the formation of dents which would be deep enough to interfere with the proper laying of the weft it is common practice to reverse the reed and also to invert it so that one reed will present four beating in surfaces to the fell of the cloth.

It is the principal object of my invention to provide a reed holder so constructed that the reed can be given a plurality of fixed vertical positions in addition to the positions which it may assume because of its reversal and inversion.

Another object of my invention is to provide a reed holder associated with auxiliary devices which serve not only to give the reed additional vertical locations but may also be housed within the reed holder to brace the latter when not in use as a housing for the reed.

A further general object of my invention is to provide means for varying the vertical position of the reed with respect to the plane of the cloth and warp at the time of beat up, the hand rail or reed cap being adjustable to accommodate the various positions of the reed.

With these and other objects in view which will appear as the description pro-

ceeds, my invention resides in the combination and arrangement of parts hereinafter described and set forth in the claims.

In the accompanying drawings, wherein I have shown one form of my invention,

55

Fig. 1 is a vertical central transverse section through a loom having my invention applied thereto;

Fig. 2 is an enlarged vertical section through the lay and reed cap showing my invention on an enlarged scale; and

Figs. 3, 4 and 5 are diagrammatic views showing the reed holder forming the subject matter of my invention in different positions.

65

Referring to Fig. 1 it will be seen that the loom side 10 supports warp beam 11 which delivers the warp 12 to the whip roll 13. The warp passes through harnesses 14, which are here shown as in the position they would occupy in a plain loom with the lay on front center as it would be at the time of beat up, the lay proper 15, breast beam 16, and take up 17 being of the usual construction. Crank shaft 18 and crank connectors 19 serve to drive the lay 15, and swords 20 which support the lay may be conveniently mounted on rocker pins 21 in any approved manner. Referring more particularly to Fig. 2 it will be seen that the lay 15 is rabbeted as at 22 to receive the back stay 23 having a slot 24 therein for a purpose to be described. The swords 20 have arms 25 which are slotted as at 26 to receive bolts 27 which pass through the hand rail 28 or reed cap 28 and are held in position by means of winged nuts 29. An upper reed holder 30 is located in a slot formed on the under face of the reed cap 28 and receives the upper end of the reed 31. The reed 31 may be of the usual construction common in certain types of looms weaving fine fabrics such as silk, but I do not wish to be limited to this form of reed inasmuch as my invention lends itself to reeds of various types.

75

My invention relates more particularly to the reed holder shown in detail in Figs. 2 to 5 and comprises a body portion 40 which is provided with a relatively deep slot 41 and a relatively shallow slot 42. A small 100

2
strip of wood or other suitable material indicated at 43 is of the proper width to be received by slots 41 and 42 without undue looseness and has a vertical dimension when 5 located in the holder which is approximately one-half the difference between the depths of slots 41 and 42.

When applying my invention to a loom the reed holder 40 will be inserted in the slot 10 24 with one of the slots therein uppermost, the slot 42 facing upwardly as shown in Fig. 2. This position of the reed holder gives the reed its highest position and corresponds to the diagrammatic representation 15 shown in Fig. 4. When the reed has been employed in this position until worn to an objectionable extent the reed holder may be withdrawn and reinserted in inverted position as shown in Fig. 5 with the strip 43 20 at the bottom of the slot 41. As indicated in the dotted line extending between Figs. 4 and 5 it will be seen that the bottom of the reed will now be somewhat lower than it was when in the position indicated in Fig. 2. A third position can be secured by removing strip 43 altogether from slot 41 at which time the reed will rest on the bottom 25 of slot 41 and will be in its lowest position. As a matter of practical convenience I have indicated that the strip 43 may be housed in the lower slot of the reed holder so that it will not only be held against loss but will also reinforce the reed holder to prevent cracking of the same.

35 From the foregoing it will be seen that I have provided a very simple holder by means of which the reed can be given several fixed vertical positions, the particular arrangement shown herein permitting the reed to assume twelve different weaving positions. Although I have shown the reed holder as being provided with only two slots and a single strip 43 yet I do not wish to be limited to this construction as the principle 40 set forth herein can be extended to afford a greater number of settings for the reed than those indicated in the drawings. Furthermore, it is possible for my invention to be practiced without the use of the strip 43.

45 The reed holder has been shown herein as located in a slot formed in the back stay, but the latter is to be considered a part of the lay and in reading the appended claims it is to be understood that the holder may be located in a slot formed in any part of the lay.

Having thus described my invention it will be apparent that changes and modifications may be made therein by those skilled 50 in the art and I do not wish to be limited to the details herein disclosed, but what I claim is:

1. In a loom, a lay, a reed, and a reed holder located on the lay, said holder having slots of unequal depth formed therein

to receive the bottom of the reed, said holder being capable of assuming a plurality of positions on said lay to locate the bottom of the reed at a plurality of levels with respect to the lay. 70

2. In a loom, a reed, a lay, a reed supporting element on the lay having a slot therein to receive one side of the reed, and a holder for the other side of the reed spaced from said element and having therein slots of different depths, said holder being capable of assuming a plurality of positions with any one of the slots therein opposite the said element to receive the other side of said reed. 75

3. In a loom, a lay having a slot therein, a reed cap mounted on said lay, a reversible reed holder in the slot in the lay, and a reed interposed between the reed cap and reed holder, the reed holder having slots in opposite portions thereof of different depths, each proportioned to receive the lower portion of the reed and said reed cap being adjustable vertically to correspond to the vertical position of the reed when said reed is received by one or the other of said slots in the reed holder. 85

4. In a loom, a lay having a reed, a slot formed therein, and a reed holder mounted in said slot and being reversible to lie in said slot in a multiple of positions, the holder having an upwardly facing slot therein for each position thereof to receive the bottom of the reed, the slots in the holder being of different depths to vary the vertical position of the reed. 100

5. In a loom, a lay, a reed, and means carried by the lay and capable of assuming a plurality of different positions with respect to the lay to hold one side of the reed, the vertical position of the reed with respect to the lay being changed with each 105 different angular position of the means.

6. A reversible reed holder for the lays of looms comprising a body portion having 110 reed receiving slots therein of different depths.

7. In a loom, a lay, a reed, a reed holder mounted on said lay and having a plurality of slots formed therein of different depths 115 to receive a portion of the reed, said holder being movable to present the slots, one at a time, to reed receiving position, and a device receivable by all of the slots in the holder and so proportioned as to form with 120 any slot in which it is located a slot the depth of which is different from the depth of the other slots.

8. In a loom, a lay, a reed, a reed holder mounted on the lay and having a slot therein to receive a portion of the reed, the holder having also another slot to receive a portion of the reed the depth of which is different from the depth of the first named slot, and a device to be received by either 125 130

slot the depth of which is approximately one-half the difference in depth of the slots.

9. In a loom, a lay, a reed, a reed holder on the lay having a plurality of slots there-
5 in of different depths, said holder being capable of assuming a plurality of positions with respect to the lay to locate any one of

the slots therein to receive one of the edges of the reed, and a device receivable by any one of the slots to form a false bottom there-
10 for and lessen the effective depth thereof.

In testimony whereof I have hereunto affixed my signature.

WALTER H. WAKEFIELD.
